UNITED STATES PATENT OFFICE.

FRANK H. STOLP, OF GENEVA, NEW YORK, ASSIGNOR TO STOLP CO., INC., OF GENEVA,
NEW YORK, A CORPORATION OF NEW YORK.

TUBE-MAKING MACHINE.

1,388,903.

Specification of Letters Patent. Patented Aug. 30, 1921.

Application filed December 18, 1919. Serial No. 345,795.

To all whom it may concern:

Be it known that I, FRANK H. STOLP, of Geneva, in the county of Ontario and State of New York, have invented certain new and useful Improvements in Tube-Making Machines; and I do hereby declare the following to be a full, clear, and exact description of the same, reference being had to the accompanying drawings, forming a part 10 of this specification, and to the reference numerals marked thereon.

My present invention relates to manufacture of metal tubes and tube-like structures and it has for its object to provide a simple 15 and efficient automatic machine that will cut the tube blanks from a continuous strip and form and deliver the tubes complete with rapidity and precision. To these and other ends the invention resides in certain improvements and combinations of parts all as will be hereinafter more fully described, the novel features being pointed out in the claims at the end of the specification.

In the drawings:

25 Figure 1 is a side view of a tube making machine constructed in accordance with and illustrating one embodiment of my invention;

30 Fig. 2 is a top plan view thereof with the driving gear partly broken away;

Fig. 3 is an enlarged fragmentary side view of one end of the machine, showing the parts in different positions from those shown in Fig. 1;

35 Fig. 4 is a top plan view of the elements shown in Fig. 3;

Fig. 5 is a further enlarged detail, longitudinal section taken on the line 5—5 of Fig. 4;

40 Fig. 6 is a fragmentary transverse section further enlarged taken on the line 6—6 of Fig. 5;

Fig. 7 is a transverse section through the seam forming dies, enlarged, on the line 45 7—7 of Fig. 5;

Fig. 8 is a transverse section through the feed clutch taken on the line 8—8 of Fig. 5, and

Fig. 9 is an enlarged transverse section 50 through the mandrel showing the completed tube in place thereon.

Similar reference numerals throughout the several views indicate the same parts.

This invention is an improvement upon 55 the machine disclosed in my Patent No.

1,327,641, dated January 13, 1920, and substantially the same general method of constructing the tube is employed herein and, briefly described, consists in bending a blank strip transversely into a U-shaped or semi-tubular form; presenting it to a mandrel having a shoulder thereon to engage its end edge and thrusting the mandrel through a guide having the form of the desired tube and provided with dies that engage the free edges of the blank and form, interlock and compress the seam. In the practice of the present invention, I feed the material to the machine in a continuous strip by means of a friction clutch; sever a blank of the desired length; thrust it from the receiving or work guide by means of a forming die into the mandrel guide, simultaneously giving it its semi-tubular form, and then thrust the mandrel and blank through the dies, the clutch, severing device, bending die and mandrel operating in timed relation from the same driving element.

In the present embodiment of the invention, the machine comprises a frame consisting 80 of a bed 1 supported on legs 2 and provided with a bracket 3 at one end supporting the bearings of a pulley shaft 4 and pulley 5 constituting the driving connection from the source of power. The usual idle pulley 85 6 is also provided and a belt shipper 7. At one end of the shaft 4 is a gear 8 meshing with and driving a toothed cam wheel 9 on a shaft 10 supported in bearings 11 on the frame. This last mentioned shaft and 90 cam wheel operate the various instrumentalities above referred to and hereinafter explained.

Mounted on the center of the bed are the associated die blocks 12 and 13 containing 95 a continuous guideway 14 (Fig. 5) for a reciprocating mandrel 15 having the retracted position shown in this figure. The die block 12 is also provided above the guide 14 with a work guide 16 shown in section in 100 Fig. 6 that is in communication therewith. This work guide 16 is in alinement with a work guide 17 formed partly by a bridge piece 18 and partly by the front rail of a frame 19 in connection with a transverse 105 guide wall 20. This bridge piece and the frame support a fixed ball clutch 21 that rests on the former in a box 22 having an inclined wedging face 23. The ball is urged to a wedging position by a plate 24 mount-

ed on a fulcrum pin 23 and a guide pin 26 carrying a spring 27. This is a stationary holding clutch. A traveling feeding clutch 28 of identical construction with respect to

5 the box 22^a, wedge face 23^a, plate 24^a, fulcrum pin 25^a, guide pin 26^a and spring 27^a reciprocates on the frame 19 on a carriage 29, the ball clutch 28 being confined within the slot or runway 30 provided by the frame 10 and the carriage has a bridge piece 31 against which the ball 28 acts.

The machine is fed from a sheet metal strip 32 wound into a roll 33 resting in a semi-cylindrical box 34 having roller bearings 35 upon which the roll rides at its periphery as it is unwound. The strip is led from the roll beneath the frame 19; between the traveling clutch elements 28 and 31; between the fixed clutch elements 21

15 and 18 and through the guide 17. The traveling clutch is reciprocated to feed one blank length of material forward and then return idly while the fixed clutch is holding the strip, by a crank arm 36 pivoted to 20 the frame at 37 and connected to the box 25

22^a of the traveling clutch by a link 38 pivoted to an eye 39 secured to said box. The crank arm is vibrated by a pitman 40 pivoted thereto at 41 and connected to a crank

30 pin 42 at its other end, said crank pin being carried on a small wheel 43 on the shaft 10. The blank or portion of the strip so fed occupies the guideway 16 in the die block 12 and is severed by a vertically reciprocating knife 44 operating between the guide walls 20 and 45 in co-operation with a blade 46 arranged beneath the guideway 17. The knife is actuated in timed relation to the feeding of the strip by a curved arm

40 46 the upper end of which is bolted rigidly thereto at 47. The lower end is slotted to receive the pin 48 on a rock arm 49 on a shaft 50 extending transversely through the frame, as shown in dotted lines in Figs. 1 45 and 3. The shaft 50 is rocked by a crank arm connection 51 at 52 with a pitman 53 the opposite end of which carries a bearing 54 running on an eccentric 55 on the shaft 10.

50 The severed blank is now in the guideway 16 of the die block 12. Upward extensions 56 thereon provide guides for the shank 57 of an elongated bending die 58 normally held above the guideway 16 by a spring 59 seated in a pocket 60 in the extensions 56 and in a central cutaway portion 61 of the die shank 57. In its downward movement, this die 58 transfers the severed blank from the work guide 16 to 60 the die guide 14 in which the mandrel 15 operates and at the same time bends it to a semi-tubular form. The die is actuated following the severing operation by an arm 62 pivoted at 63 on a bracket arm 64 on the 65 frame of the machine. This arm 62 has a

loose pivotal connection with the die shank at 64^a and the other end is provided with a roller 65 running in a cam track 66 on the cam wheel 9.

After the die has risen (the spread lateral edges of the blank being retained by shoulders 66 within the guideway 14, Fig. 6) the mandrel 15 moves forwardly into the guide 14 and to a position within the partially formed blank. A shoulder 67 on the mandrel abuts the lower end edge of the blank and is accommodated within a similarly formed lower extension 68 of the guideway 14. This thrusts the blank through the die blocks 12 and 13, the latter of which, as shown in Fig. 7, carries creasing dies 69, 70 and 71 secured thereto by bolts 72 and of such conformation as to progressively act to form, engage and flatten the seam 73 shown in Fig. 9 on the finished tube 74. The 85 mandrel is actuated by a connecting rod 75 having a bearing on a wrist pin 76 on a cross head 77 guided on the bed and having a bearing 78 on a crank pin carried by an extension 79 of the cam wheel 9. 90

I claim as my invention:

1. In a tube forming machine, the combination with a bed, a guideway provided with tube forming dies and a mandrel operating in the guideway and provided with a shoulder to engage the end of the blank and thrust it through the dies, of a work guide extending longitudinally of the die guide and communicating therewith, means for feeding the blank therethrough and means for thrusting a blank from the work guide into the die guide between the dies and the mandrel. 95

2. In a tube forming machine, the combination with a bed, a guideway provided with tube forming dies and a mandrel operating in the guideway and provided with a shoulder to engage the end of the blank and thrust it through the dies, of a work guide extending longitudinally of the die guide and communicating therewith, means for feeding a continuous strip of metal therethrough, a severing device adapted to cut a blank of the desired length from the strip, and means for thrusting the blank from the work guide into the die guide between the dies and the mandrel. 110

3. In a tube forming machine, the combination with a bed, a guideway provided with tube forming dies and a mandrel operating in the guideway and provided with a shoulder to engage the end of the blank and thrust it through the dies, of a work guide extending longitudinally of the die guide and communicating therewith, means for feeding a continuous strip of metal therethrough, a severing device adapted to cut a blank of the desired length from the strip and a bending die movable transversely in both guideways to bend the severed blank 120 125 130 135 140 145 150 155 160 165 170 175 180

into semi-tubular form and thrust it into the die guide.

4. In a tube forming machine, the combination with a bed, a guideway provided with tube forming dies, a mandrel operating in the guideway and provided with a shoulder to engage the end of the blank and thrust it through the dies, and a work guide extending longitudinally of the die guide and communicating therewith, of a reciprocating clutch for feeding a continuous metal strip through the work guide, a severing device adapted to cut a blank of the desired length from the strip, a bending die movable transversely in both guideways to bend the severed blank into semi-tubular form and thrust it into the die

guide, a rotary element on the bed and crank connections from the rotary element to the clutch, severing device and bending die for operating them successively in timed relation. 20

5. In a tube forming machine, the combination with a guideway provided with tube forming dies and a mandrel adapted to thrust a blank through the guideway, of a work guide, a carriage provided with a ball clutch adapted to feed a continuous strip of metal through the work guide in the direction of thrust of the mandrel and a guide for the carriage having a longitudinal slot for confining the ball of the ball clutch. 25 30

FRANK H. STOLP.
